UNITED STATES PATENT OFFICE.

JOHN H. ELWARD, OF WHITEWATER, WISCONSIN.

ENGINE-VALVE.

SPECIFICATION forming part of Letters Patent No. 375,144, dated December 20, 1887.

Application filed January 4, 1887. Serial No. 223,353. (No model.)

To all whom it may concern:

Be it known that I, JOHN H. ELWARD, a citizen of the United States, residing at White-water, in the county of Walworth and State 5 of Wisconsin, have invented certain new and useful Improvements in Engine-Valves, of which the following is a specification, reference being had therein to the accompanying drawings.

10 Figure 1 is a longitudinal section of so much of an engine as is required to show my invention. Fig. 2 is a plan view of the steam-chest. Fig. 3 is a plan view of some of the parts. Fig. 4 is an end elevation of the interior parts. 15 Fig. 5 is a section of the anti-friction devices. Fig. 6 is a longitudinal section of a modification. Fig. 7 shows a modification of the vertical rods secured to the valve and of cross-bars at the top.

20 Like letters of reference indicate similar parts in all the figures.

The object of the invention is to relieve in whole or in part the friction between a slide-valve and its seat in a steam-engine, and one 25 part thereof relates to a novel construction of the devices whereby certain of the adjustments can be effected without opening the steam-chest and while the valve is under steam-pressure.

30 Other parts of the invention relate to various new features of construction, which will be hereinafter specifically pointed out.

A represents generally the valve seat, provided with steam-ports.

35 B is the slide-valve.

C is the valve-rod or valve-stem, which part may be of any usual or approved construction adapted to have my invention applied thereto, and therefore need not be specifically described.

40 D are rods, two or more, projecting upward from the valve B. These rods are screw-threaded at their lower ends and can be adjustably secured to the valve. The upper ends pass through transverse bars or plates E

45 and are provided in the construction shown with nuts whereby they can be adjustably suspended from said bar; or, the nuts may be dispensed with and the upper ends of the rods 50 D may be slotted and expanded conically and fitted in countersunk apertures in the bars E, the slots permitting the application of a turn-

ing-tool and the countersunk heads allowing the bars D to be kept flush with the bars E.

G G are adjustable suspension-bars hung 55 from the top plate or cap, H, of the steam-chest by means of rods or hangers I I, each of which is screw-threaded at its lower end, where it takes into a screw-threaded hole in said suspension-bar. Each suspension-bar is 60 grooved upon its upper face, as at g. (See Fig. 4.)

The upper end of each suspension-rod I is squared or otherwise adapted to receive a wrench or other device for turning it, and is 65 further provided near its upper end with a flange or collar, i, resting upon the upper surface of the steam-chest cap or top plate, which has openings to receive these suspension-rods.

70 The cap of the steam-chest is provided with sockets K K for each suspension-rod, and, by preference, the walls of the sockets project above the general level of the cap H. These sockets are screw-threaded internally to receive the glands L L, which are screw-threaded externally and are hollow to permit the passage of the suspension-rods through them.

75 Packings may be used in the sockets to form a stuffing-box joint of such character that the escape of steam at this point may be easily prevented. I do not, however, wish to be limited to this precise construction of parts, because the socket K might be under some circumstances dispensed with, or the upper face 80 of the cap or cover H might be recessed at those points, or the supporting-rods I might be made to fit the openings steam-tight. The lower end of each rod I is screw-threaded and takes into a corresponding threaded hole, m, 90 of which there is one in each end of a transverse bar, M. There are two of these bars M, and the suspension-bars G G are bolted to the under sides thereof, or, when preferred, the bars G G may be placed on top of the bars M 95 and secured thereto.

N is a toothed bar arranged about midway between the suspension-bars G and bolted at its ends to the bars M M, with its teeth n n substantially in vertical planes, for a purpose to 100 be explained. There may be a corresponding toothed bar arranged between the two upper bars, F F, and parallel therewith.

O O are anti-friction wheels formed in pairs

upon axles P P and integral therewith. These wheels run on the tracks F F and bars G.

Q is a pin-gear, also cast integrally with shaft P, with its teeth q engaging with the toothed bar N n.

- From an examination of the drawings and the foregoing description it will be understood that by turning the suspension-rods I in the proper direction the bearing of the valve upon 10 the valve-seat can be so regulated as to materially relieve the friction between those parts without producing any leakage of steam, and this adjustment can be effected without opening the steam-chest by applying a wrench to 15 the upper squared ends of the suspension-rods I. This capability of adjusting the pressure of the valve upon the valve-seat becomes very important in view of the unequal or irregular expansion of the steam-chest as it becomes 20 heated and of other irregularities which make it very difficult to properly adjust the relative positions of the grooved plates and the anti-friction wheels prior to putting on the cap of the steam-chest.
- 25 The presence of the pin gear-wheel and the engaging rack-teeth is a safeguard against the accidental displacement of the anti-friction wheel.

In Fig. 6 I have shown a modification in 30 which the vertical adjustment of the suspension-bars G is effected by pointed set-screws S S, which are mounted in the side walls, R R, of the steam-chest in such position that the points of the screws bear against the under 35 sides or surfaces of the suspension-bars, which latter may be forced away from the valve-seat by screwing the set-screws inward.

T T t are diagonal braces, each expanded at both ends into eyes, loops, hooks, or ears 40 adapted to engage with the suspension-rods I I. These braces are secured to each other at the crossing-points and serve to maintain the suspension-bars in parallel planes, thereby insuring a uniformity of movement between the 45 valve and the track-bars F.

By preference I can construct the side walls with bosses or re-enforcements r r at the points where the set-screws pass through; but in many cases these may be omitted, because the ordinary walls of the steam-chest will provide a sufficiently strong support. Of course stuffing-boxes similar to those shown at K may be used to guard against leakage around these set-screws.

55 By preference I make the bars G G to fit closely at their ends the end walls of the steam-chest, and the bars M M fit closely at their ends the side walls of the steam-chest, and thus prevent lateral movement of these parts, while 60 they are free to rise and fall as the rods I I are turned in one direction or the other.

While I have shown my invention as applied to a horizontally-moving valve within a steam-chest arranged upon the upper side of 65 the cylinder, I do not wish to be limited to such arrangement of parts, because it is adapted

for use upon valves which are located on the sides of the cylinders with either a horizontal or vertical movement.

Although I have shown but two constructions for the carrying out of my invention, I do not wish to be limited thereby, because many modifications will naturally suggest themselves to a skilled mechanic without in any manner departing from that part of my invention 75 which relates to mounting the adjusting devices in the walls of the cap of the steam-chest with portions of the adjusting devices projecting outside thereof, so that they can be operated without removing the cap or top plate. 80

What I claim is—

1. The combination, with the sliding valve and the steam-chest, of the rods D, secured to the valve, the upper guide-bars, E, carried by said rods D, the anti-friction wheels O, the lower track-bars, G, and the supporting-rods I, rigidly secured to the wall of the steam-chest, substantially as set forth.

2. The combination, with the valve and the steam-chest, of the rods D, the upper guide-bars, F, the grooved anti-friction wheels O, the lower suspension-bars, G, the toothed wheel Q, supplemental to the wheels O, and the rack N, substantially as set forth.

3. The combination, with the steam-chest, of 95 the anti-friction rollers, the valve suspended upon the said rollers, the rollers being arranged in two or more pairs, and the rollers of each pair being connected rigidly together, and the toothed rack and wheel intermediate 100 of the rollers, substantially as and for the purposes set forth.

4. The combination, with the steam-chest and the valve, of the anti-friction rollers upon which the valve is suspended, said rollers being arranged in two or more pairs, and the rollers of each pair being formed integral with the shaft, and the intermediate guide-wheel, Q, substantially as set forth.

5. The combination, with the steam-chest 110 and the valve, of the suspension-bars G, rigidly secured to the steam-chest, the anti-friction rollers O, arranged in pairs, each pair having a transverse shaft, P, which unites together the rollers, and the supporting devices 115 which hold the valve and rest upon the said anti-friction rollers, as described.

6. The combination, with the steam-chest and the valve, of the suspension-bars G, the anti-friction rollers resting upon the said bars, 120 the guide-bars F, resting upon said rollers, and means, substantially as described, for detachably connecting the said guide-bars to the valve, as set forth.

7. In the balance mechanism for valves, the 125 herein-described anti-friction rollers and guide-wheel Q, intermediate of the rollers, cast integrally together, and the reduced shaft P between the guide-wheels, substantially as set forth.

8. The combination, with the steam-chest and the valve, of the anti-friction rollers O O, 130

arranged in pairs, the shaft joining the rollers of each pair, supporting means for the suspension-bars, the rack-bar N, intermediate of the rollers O and carried by said supporting means, and the toothed wheel engaging with said bar, as described.

9. The combination, with the steam-chest and the valve, of the anti-friction rollers, the rack having laterally-projecting teeth, and the guide-wheel having corresponding laterally-projecting teeth, substantially as set forth.

10. The combination, with the steam-chest and the valve, of the anti-friction rollers O O, in pairs, one of each pair on one side of the

chest and the other upon the other, the suspension-bars G, the transverse connecting-bars M, forming a rectangular frame, the bars G, the bars F, and the cross-bars E, forming, with the bars F, an upper rectangular frame, and the devices which suspend the valve from the said frame E F, substantially as set forth.

In testimony whereof I affix my signature in presence of two witnesses.

JOHN H. ELWARD.
